UNITED STATES PATENT OFFICE.

ALBERT ELMER HARKER, OF WINDSOR, NEW JERSEY.

ENVELOP.

No. 922,891.

Specification of Letters Patent.

Patented May 25, 1909.

Application filed January 15, 1909. Serial No. 472,430.

To all whom it may concern:

Be it known that I, ALBERT E. HARKER, a citizen of the United States, and a resident of Windsor, in the county of Mercer and State of New Jersey, have invented a new and Improved Envelop, of which the following is a full, clear, and exact description.

The purpose of this invention is to produce a novel, inexpensive and shapely envelop from a single sheet of paper, that may be rapidly cut, folded into form and secured by an adherent at certain edges thereof, so as to provide two independent pockets therein for the reception of cash contributions to different objects, the envelop being especially designed for use in the collection of voluntary offerings for the support of a pastor, and other purposes of a benevolent nature, and which are usually collected and disbursed by the officers of a church; a further object being to provide suitable spaces on the envelop for the reception and display of church notices, current texts of scripture, or other appropriate advertisements that may be written or printed thereon.

The invention consists in the novel construction of an envelop from a single sheet of paper, as is hereinafter described, and defined in the appended claims.

Reference is to be had to the accompanying drawings forming a part of this specification, in which similar characters of reference indicate corresponding parts in all the views.

Figure 1 is a plan view of the blank for the improved envelop, cut into form and partially folded; Fig. 2 is an inner side view of the envelop, showing half portions thereof folded together; Fig. 3 is a rear face view of the envelop folded and ready for closure and sealing; Fig. 4 is an enlarged longitudinal sectional view of the sealed envelop, taken on the line 4—4 in Fig. 7; Fig. 5 is an enlarged longitudinal sectional view, substantially on the line 5—5 in Fig. 3; Fig. 6 is a plan view of the envelop unfolded to display its two main sections, on the side opposite that shown in Fig. 2, and Fig. 7 is a front face view of the improved envelop completely folded and sealed.

The blank A, as cut from a paper sheet for the production of the improved envelop, comprises an oblong piece of paper, having four edges that are disposed oppositely in pairs, as shown in Fig. 1. The width between the edges *a* and *b* of the blank A, is greater than that between the edges *c*, *d*

thereof. Parallel with the edge *b* and near it a fold *b'* is formed, producing a narrow flap *b'* that is coated on one side with a suitable sealing material, as shown at *b''* in Fig. 1. The blank A is folded at *e*, *e* centrally between the edge *a* and fold *b'*, and the edge portion near the edge *a* is imposed upon the flap *b'* whereon it is secured by the adhesive coating *b''*. The portion B of the blank A defined in width by the edge *a* and fold *e*, *e*, is provided with similar flaps *g*, *h*, that project at the respective ends of said blank when it is cut into form. The flap *g* having a coating of adhesive on the outer surface thereof as shown at *g'* in Fig. 1, is designed to fold down upon the portion B, and as is indicated in Fig. 1 a flap *h* is adapted for folding toward the opposite side of the portion B from that on which the flap *g* is folded. The remaining half section C of the blank A, which for convenience is designated by the character C, is provided with a flap *i* of greater breadth than the flap *h*, and in service is folded on the line *i'*, *i'* that appears in Figs. 1 and 6. The flap *i* is coated with adhesive material on the side shown in Fig. 1, as indicated at *i''*. Near the edge *m* which is parallel with and opposite to the fold line *i'*, *i'* a slot *n* is formed in the blank section C. Centrally between the fold line *i'*, *i'* and edge *m*, the folded sections B, C are again folded on a line *o*, *o* which is parallel with the fold line *i'*, *i'*. A coating *p* of adhesive is formed on the section B, at and near the fold line *o*, *o*, and when the sections B, C are folded together on the line *e*, *e* said adhesive is adapted for joining together said blank sections at or near the fold line *o*, *o*.

As before mentioned, the edge portion *a* of the blank section B is cemented upon the flap *b'* by the adhesive *b''* when the sections B, C are folded together on the line *e*, *e*, and when this is being effected the adhesive *g'* on the flap *g* is caused to cement said flap upon the edge portion of the blank section C adjacent to the slot *n*. It will be seen that when the blank sections B, C are folded, and certain edge portions thereof are cemented together as heretofore explained, two receptacles *r*, *s* are formed in the envelop, that are side by side, one receptacle *r* having the slot *n* opening thereto, and the other receptacle *s* is closed by folding down and sealing the flap *i* over the folded flap *h*. The pocket or receptacle *s* is designed for reception of church support such as the pastor's salary and current expenses. Through the slot *n* contrib-

butions of a benevolent character are placed in the receptacle *r*, such as local charities and the missionary fund, and it will be noted that the flap *i* when folded down and sealed, closes the slot *n* and thus prevents the contents of the receptacle *r* from inspection only by the proper officer of the church.

As shown, written or printed instructions are placed on the front and rear faces of the envelop, and as the envelop when distributed for the reception of contributions is not completely folded but is in the condition shown in Fig. 2, it will be obvious that advertisements of an appropriate character may be placed on the surface shown exposed in Fig. 2.

The improved envelop is manifestly extremely simple, provides two independent sealable pockets formed of one piece of paper; permits the abstraction of the contents of one pocket without disturbance of the contents of the other pocket; provides means for sealing both pockets at the same time by one operation; and requires the return of the entire sealed envelop and its contents to the church officer at the same time. By reason of its extreme simplicity, each person using the improved envelop may without mistake place the contribution in the proper receptacle for the purpose intended.

While preferably used for the purpose designated, the improved envelop may also be employed for other purposes.

Having thus described my invention, I claim as new and desire to secure by Letters Patent:

1. An envelop made from a sheet doubled

upon itself to form two folds, one of said folds having at its free side edge a flap for engaging the free side edge of the other fold, one end of said first named fold being provided with a flap, and the other with a slot, the ends of the other fold being each provided with a flap of lesser length than the end flap of the first named fold, the flap adjacent to the slot being provided with an adhesive for securing it to the end of the other fold, said fold having at its center a transverse line of adhesive, said folds being doubled upon themselves to form a two part envelop, said long fold being the sealing flap and of a length sufficient to cover the slot.

2. An envelop made from a sheet doubled upon itself to form two folds, one of said folds having at its free side edge a flap for engaging the free side edge of the other fold, one end of said first named fold being provided with a flap, the ends of the other fold being each provided with a flap of lesser length than the end flap of the first named fold, the flap adjacent to the slot being provided with an adhesive for securing it to the end of the other fold, said fold having at its center a transverse line of adhesive, said folds being doubled upon themselves to form a two part envelop, the long fold being the sealing flap.

In testimony whereof I have signed my name to this specification in the presence of two subscribing witnesses.

ALBERT ELMER HARKER.
